CARTON

Louis L. Zimmerman, Jacksonville, Fla., assignor
to Herring Ginger Ale, Inc., Jacksonville, Fla.,
a corporation of Florida

Application July 29, 1936, Serial No. 93,276

12 Claims. (Cl. 229—52)

The present invention relates particularly to a carton for the packaging of necked containers, such as bottles, and, more particularly, bottles of the type currently used in the marketing of 5 beverages, such as ginger ale. The new carton, hereinafter to be described in detail with reference to the accompanying drawing, is especially economical in manufacture, effective in protecting and displaying the containers, and advancing 10ageous in handling.

In the drawing,

Figure 1 is a perspective view of the new carton, the carton being closed.

Figure 2 is a view similar to that of Figure 1, 15 but showing the top of the carton in open position.

Figure 3 is a section substantially on line 3—3 of Figure 1, and

Figure 4 is a face view of a blank from which 20 the carton may be most conveniently made.

For the purposes of this description, it will be assumed that the carton shown in Figures 1 to 3 is formed from the blank of Figure 4, although actually the carton may be built up from 25 a number of separate blanks.

The blank shown in Figure 4 has substantially the form of a rectangle and is of any suitable material. Generally, the material will be relatively rigid in nature, so that the carton will 30 retain its prescribed form in use, appropriate materials, to this end, being cardboard, reinforced paper, corrugated paperboard, etc. The blank comprises the panels 10, 11, 12, and 13, the latter having a projecting wing 14 integral 35 therewith but demarked, desirably, by a score or fold line 15. The panels themselves are demarked by the score lines 16, 17, and 18, parallel to the line 15.

The panels have extensions 19, 20, 21, and 22 40 demarked by the continuous score or fold line 23, perpendicular to line 15, and are separated from each other by the slits 24, 25 and 26 which are aligned with the score lines 16, 17 and 18, respectively.

45 Panels 10 and 12 are continued into extensions or flaps 27 and 28 demarked by the aligned score lines 29 and 30 parallel to line 23, the length of these extensions being equal, or substantially so, to the width of the similar panels 11 and 13.

50 Panels 11 and 13 are continued into extensions or flaps 31 and 32 demarked by the aligned score lines 33 and 34 parallel to line 23, these extensions having a length equal, or substantially so, to the width of the similar panels 10 and 12.

55 Extension 31 is separated from the adjacent ex-

tensions and panels by the slits 35 and 36, and extension 32 is separated from the adjacent extension and panel by the slit 37.

Extension 32 is provided with a pair of elongated slots 38 and 39 which extend in parallel relation to the slit 37. Slot 38 is spaced from slit 37 a distance at least equal to the distance between the sides of the neck and body of a container, such as a ginger ale bottle as indicated at 40, Figure 1, and slot 39 is similarly spaced from the adjacent edge of extension 32. The slots are spaced apart about twice the distance they are spaced from the adjacent edges of the extension. Extension 31 is provided with exactly similar slots.

Extension 27 is provided with a pair of slots 41 and 42 which extend parallel to fold line 29. The slots are symmetrically positioned and sufficiently spaced apart so as to leave a strip 43 of substantial width between them. They are 10 smaller, as here shown, than the slots 38, 39.

The outer edges of extension 27 are provided with notches 44 and 45 so as to provide parallel edges spaced inwardly from the lateral edges of the extension. Extension 27 is also provided 20 with a pair of obliquely extending slits or narrow slots 46 and 47 which extend from fold line 29 to adjacent the lateral edges of the extension, terminating a distance from these edges at least equal to the distance of the edges of notches 44 25 and 45 therefrom. Extension 28 has exactly the same provision of slots, notches and slits as extension 27.

In assembly, the blank is bent on the lines 16, 17 and 18 so as to bring panel 12 in parallel 35 relation to panel 10 and panel 13 into similar relation with panel 11, the tongue 14 being secured by any suitable means to the inner margin of panel 10, Figure 3, so that the panels become side walls arranged as the sides of an upright 40 rectangular parallelepiped. Wings 19 to 22 are folded inwardly and interleaved in substantially rectangular relation to the panels 10 to 13, and secured together in any suitable manner so as to form the bottom of the carton, which now has 45 substantially the form shown in Figure 2 of the drawing.

The illustrated carton is designed to receive six bottles in two rows of three each, and its proportions, of course, depend on the size of the 50 bottles. The bottles having been placed in the carton, extension or flap 31 is folded over on line 33 to a position at right-angles to panel 11, i. e., to horizontal position, so that the necks of the bottles are engaged in the slots. Extension 55

or flap 32 is then similarly folded, and it may be provided with a struck-out tongue 48 engageable in a slit 49 in flap 31, Figures 3 and 4, so that the two flaps will be held together. The 5 slots as at 38 and 39 thus engage the necks of the bottles to position the same against undue relative movement and thereby reduce the danger of breakage.

Flap 28 may now be bent to a position at right-10 angles to panel 12 and its outer corners inserted from below in the slots 46 and 47 of flap 27 which is simultaneously bent over to have its outer corners inserted from above in the similar slits of flap 28, the two flaps being thus interlocked to 15 form a top wall for the carton.

The slots as at 41 and 42 of flaps 21 and 32 are 20 in register and are so positioned above the tops of the containers that the latter are visible in substantial register with the slots as at 38, 39 so that the contents may be identified. The strip 25 portions as at 43 constitute a gripping portion or handle by means of which the carton may be lifted, the hand being readily insertable through the slots.

It will be evident that the blank of Figure 4 is 30 of very economical design, since it is substantially rectangular. The only part projecting beyond the outline of the rectangle is the tab 14 and wastage in this respect is substantially eliminated, in cutting the blanks from a strip, by reversing the succeeding blank at the right of Figure 4 so that its tab 14 comes above the tab 14 illustrated. The material eliminated by the notches as at 44 and 45 is inconsequential, and it will be 35 understood that the notches are provided in order that the slits as at 46 and 47 may terminate inwardly a sufficient distance from the tab edges so as not to be readily torn through.

The horizontal wall formed by flaps 31 and 32 40 serves in conjunction with the enclosing side walls of the carton to prevent undue relative movement of the containers so that breakage is reduced to a minimum. The top horizontal wall constituted by flaps 27 and 28 protects the tops 45 of the bottles, while at the same time leaving them clearly visible.

A further and extremely important feature of the described carton is that since the top wall is flat, the cartons, when made of relatively rigid 50 material, can be securely stacked in upright position without buckling of the vertical walls.

As stated at the outset, the carton need not necessarily be made from a single blank as shown in Figure 4, and obviously the carton may be of a 55 size to accommodate different numbers and sizes of bottles, and I do not limit myself to these details except as in the following claims. In the claims, I refer to the upright position of the side panels and to the horizontal disposition of the 60 top and intermediate walls purely as a matter of convenience and in reference to the normal position of the carton in use.

I claim:

1. A carton for necked containers, said carton 65 comprising upright enclosing walls and a bottom wall, an apertured horizontal wall through which the necks of the containers project in use and above which a pair of opposite ones of said enclosing walls project, and an apertured top horizontal wall through which the upper ends of the containers are visible, said top wall being joined to the upper ends of said opposite ones of said projecting enclosing walls, said apertured horizontal walls and said opposite ones of said projecting enclosing walls defining an open ended 70

passage through the ends of which the necks of the containers may be visible.

2. A carton for necked containers, said carton comprising upright enclosing walls and a bottom wall, an apertured horizontal wall through which the necks of the containers project in use and above which a pair of opposite ones of said enclosing walls project, and an apertured top horizontal wall through which the upper ends of the containers are visible, said top wall being joined to the upper ends of said opposite ones of said projecting enclosing walls and being apertured in such a manner as to provide a gripping portion, said apertured horizontal walls and said opposite ones of said projecting enclosing walls defining an open ended passage through the ends of which the necks of the containers may be visible. 15

3. A carton for necked containers, said carton being in the form of an upright rectangular parallelepiped and comprising side walls, a bottom wall, an apertured horizontal wall through which the necks of the containers project in use, said horizontal wall joining the upper ends of opposite ones of said side walls, the other side walls 20 projecting above said opposite ones of said side walls, and an apertured top horizontal wall joining the upper ends of said other side walls and through which the upper ends of the containers 25 are visible. 30

4. A carton for necked containers, said carton being in the form of an upright rectangular parallelepiped and comprising side walls, a bottom wall, an apertured horizontal wall through which the necks of the containers project in use, said horizontal wall joining the upper ends of opposite ones of said side walls, the other side walls 35 projecting above said opposite ones of said side walls, and an apertured top horizontal wall joining the upper ends of said other side walls and through which the upper ends of the containers 40 are visible, said top wall being apertured in such a manner as to provide a gripping portion. 45

5. A carton for necked containers, said carton being in the form of an upright rectangular parallelepiped and comprising side walls, a bottom wall, an apertured horizontal wall through which the necks of the containers project in use, said horizontal wall joining the upper ends of opposite ones of said side walls, the other side 50 walls projecting above said opposite ones of said side walls, and an apertured top horizontal wall joining the upper ends of said other side walls and through which the upper ends of the containers are visible, both of said horizontal walls comprising bent-over flaps constituting extensions of the respective side walls. 55

6. A carton for necked containers, said carton being in the form of an upright rectangular parallelepiped and comprising side walls, a bottom wall, an apertured horizontal wall through which the necks of the containers project in use, said horizontal wall joining the upper ends of opposite ones of said side walls, the other side walls projecting above said opposite ones of said side walls, and an apertured top horizontal wall joining the upper ends of said other side walls and through which the upper ends of the containers are visible, said top wall comprising overlapped flaps constituting extensions of said other 60 side walls. 65

7. A carton for necked containers, said carton being in the form of an upright rectangular parallelepiped and comprising side walls, a bottom wall, an apertured horizontal wall through 70

which the necks of the containers project in use, said horizontal wall joining the upper ends of opposite ones of said side walls, the other side walls projecting above said opposite ones of said side walls, and an apertured top horizontal wall joining the upper ends of said other side walls and through which the upper ends of the containers are visible, said top wall comprising overlapped and interlocked flaps constituting extensions of said other side walls.

8. A carton for the packaging of a plurality of rows of necked containers, said carton being in the form of an upright rectangular parallelepiped and comprising side walls between which the rows of containers are receivable in juxtaposition, a bottom wall, a horizontal wall having slots through which the necks of the rows of containers respectively project, said horizontal wall joining the upper ends of opposite ones of said side walls, the other side walls projecting above said opposite ones of said side walls, and a top horizontal wall joining the upper ends of said other side walls, said top wall having slots substantially in register with the first-mentioned 10 slots, the wall portion between adjacent slots serving as a gripping portion.

9. A carton for the packaging of a plurality of rows of necked containers, said carton being in the form of an upright rectangular parallelepiped 30 and comprising side walls between which the rows of containers are receivable in juxtaposition, a bottom wall, a horizontal wall having slots through which the necks of the rows of containers respectively project, said horizontal wall joining the upper ends of opposite ones of said side walls, the other side walls projecting above said opposite ones of said side walls, and a top horizontal wall joining the upper ends of said other side walls, said top wall having slots substantially in register with the first-mentioned 35 slots, the wall portion between adjacent slots serving as a gripping portion, both of said horizontal walls comprising bent-over flaps constituting extensions of the respective side walls.

10. A carton for the packaging of a plurality of rows of necked containers, said carton being in the form of an upright rectangular parallelepiped and comprising side walls between which the rows of containers are receivable in juxtaposition, a

bottom wall, a horizontal wall having slots through which the necks of the rows of containers respectively project, said horizontal wall joining the upper ends of opposite ones of said side walls, the other side walls projecting above said opposite ones of said side walls, and a top horizontal wall joining the upper ends of said other side walls, said top wall having slots substantially in register with the first-mentioned 5 slots, the wall portion between adjacent slots 10 serving as a gripping portion, said top wall comprising overlapped flaps constituting extensions of said other side walls.

11. A carton for the packaging of a plurality of rows of necked containers, said carton being 15 in the form of an upright rectangular parallelepiped and comprising side walls between which the rows of containers are receivable in juxtaposition, a bottom wall, a horizontal wall having slots through which the necks of the rows of 20 containers respectively project, said horizontal wall joining the upper ends of opposite ones of said side walls, the other side walls projecting above said opposite ones of said side walls, and a top horizontal wall joining the upper ends of 25 said other side walls, said top wall having slots substantially in register with the first-mentioned slots, the wall portion between adjacent slots 30 serving as a gripping portion, said top wall comprising overlapped and interlocked flaps constituting extensions of said other side walls.

12. A carton for necked containers, said carton being formed from a substantially rectangular blank of suitable material folded to provide side walls arranged as the sides of an upright rectangular parallelepiped and also to provide a bottom wall, opposite ones of said side walls having top extensions bent to horizontal position and the extensions having slots through which the container necks project in use, the other side walls 40 projecting above said opposite ones of said side walls and having top extensions bent to and interlocked in horizontal position to form a top wall above the container tops, said top wall being provided with slots in substantial register with 45 the first-named slots and through which the container tops are visible, a gripping portion existing between the slots of said top wall.

LOUIS L. ZIMMERMAN.
